CLAIM

The ornamental design for a stress resistant battery, as shown and described.

DESCRIPTION

FIG. 1 is a perspective view of a stress resistant battery in accordance with the present invention;

FIG. 2 is a front plan view of stress resistant battery in accordance with the present invention;

FIG. 3 is a side plan view of a stress resistant battery which by symmetry depicts both left and right sides in accordance with the present invention;

FIG. 4 is a rear plan view of a stress resistant battery in accordance with the present invention;

FIG. 5 is a top plan view of a stress resistant battery in accordance with the present invention; and,

FIG. 6 is a bottom plan view of a stress resistant battery in accordance with the present invention.

As noted above, by symmetry, FIG. 3 depicts both left and right sides of the present invention.
